(57) **CLAIM**

The ornamental design for a mobile communication terminal with animated graphical user interface, as shown and described.

DESCRIPTION

FIG. 1 is a first image of a first embodiment of a mobile communication terminal with animated graphical user interface showing our new design;

FIG. 2 is a second image thereof;

FIG. 3 is a first image of a second embodiment of the mobile communication terminal with animated graphical user interface;

FIG. 4 is a second image of the second embodiment;

FIG. 5 is a first image of a third embodiment of the mobile communication terminal with animated graphical user interface; and,

FIG. 6 is a second image of the third embodiment.

The broken lines shown in the drawings of a mobile communication terminal and certain graphic features of the animated graphical user interface form no part of the claimed design.

The appearance of the transitional image sequentially transitions between the images shown in FIGS. 1-2, 3-4 and 5-6. The process or period in which one image transitions to another image forms no part of the claimed design.

1 Claim, 6 Drawing Sheets
